ATTORNEY

UNITED STATES PATENT OFFICE.

PATRICK J. CAHILL, OF UTICA, NEW YORK.

HANGER-HANDLE FOR ELECTRIC LIGHTS.

SPECIFICATION forming part of Letters Patent No. 764,037, dated July 5, 1904.

Application filed September 17, 1903. Serial No. 173,556. (No model.)

To all whom it may concern:

Be it known that I, PATRICK J. CAHILL, of Utica, in the county of Oneida and State of New York, have invented certain new and useful Improvements in Hanger-Handles for Electric Lights; and I do hereby declare that the following is a full, clear, and exact description thereof, which will enable others skilled in the art to which it appertains to make and use the same, reference being had to the accompanying drawings, and to the letters and figures of reference marked thereon, which form part of this specification.

The object of my invention is to provide a means for handling incandescent electric lights without danger of shock from overcharge of electricity and incidentally provide a means for suspending or holding the lamp.

In the drawings, Figure 1 shows a side elevation of a lamp having my improvements applied and shown in suspended position on a suitable stand-hanger. Fig. 2 shows the lamp shown in Fig. 1 in position at right angles thereto. Fig. 3 shows a portion of the device shown in Figs. 1 and 2 supported on a hook attached to the conductor-cord. Fig. 4 shows the same as Fig. 3 in position at right angles thereto. Fig. 4^a shows a plan view of the hook and lamp shown in Figs. 3 and 4. Fig. 5 shows a vertical section of the devices in connection with a lamp. Fig. 6 shows inside face view of one of the parts of the holder or hanger device with the conductors in position therein, and Fig. 7 shows inside face view of other similar parts. Figs. 8 and 9 show side and edge elevation of a modified form of construction.

Referring to the reference letters and figures in a more particular description, 1 indicates the ordinary incandescent-lamp bulb, and 2 the ordinary socket thereof. In the construction shown in Figs. 1 to 5, inclusive, the lamp-socket is the usual metal socket. The conductor cords or wires 3 3 may or may not be contained in the same cable and enter the top of the lamp-socket in the usual manner. I provide the two-part holding and hanging device 4, the parts of which are provided with grooves or recesses *a* in the meeting faces, adapted to receive the conductor

wires or cords 3 3, and are also provided at each end with semicircular sleeve-like extensions *b* *b*, one of which is adapted to be received in the opening in the end of the socket. Through the sleeve portions *b* extend the 55 openings *c* *c*, through one of which the conductors enter the part 4 and through the other of which they pass into the body of the socket.

For securing the parts of the holder together, as well as securing them in position on the socket, there is provided a set-screw 5 in the ferrule portion in the upper end of the socket. Other means for securing the parts together, as small bolt 6, may be provided. 65 The holder 4 is provided with an opening *d*, which is adapted to receive a supporting-hook. The two conductors diverge after entering the part 4 and pass around the opening *d*. The holder 4 is made of insulating material, and by means of the holder the lamp can be safely handled, even when charged or overcharged by a short-circuited or otherwise-produced electric current.

In Fig. 1 at A is shown a suitable suspending device for the lamp adapted for table or desk use. For other uses I provide a pair of clamping-blocks B, which may be clamped at any suitable point on the conductor cords or wires, which usually hang down from the ceiling. The clamp B is provided with a hook *h*, adapted to be passed through the opening *d* in the holder 4, and thereby the lamp can be conveniently supported. A series of clamps B, having the hook *h*, can be provided 85 on the same conductor, if desired.

In the modified form of construction shown in Figs. 8 and 9 the modified form of socket 2' is shown. This socket is usually of porcelain. In connection with this form of construction my 90 hanger 4^a consists of a somewhat similar pair of parts to those heretofore described, except that they are clamped on the conductors 3^a 3^a only in order to secure them to the lamp and are provided with a shoulder *s* at the end, 95 which engages the lamp-socket, and when abutting snugly against the end of the lamp-socket serve to provide a suitable handle.

It is evident that other modified forms of construction than that herein shown may be 100

provided without departing from the spirit of my invention. By using the hanger-handle described electric lights may be safely and conveniently handled or suspended without 5 fear of an electric shock.

What I claim as new, and desire to secure by Letters Patent, is—

1. The combination with an incandescent-electric-lamp socket of an insulated handle, 10 consisting of two separable parts, having projecting portions engaging in the usual opening in the end of the socket, and having channels in the meeting faces to receive the conductor-wires and formed to provide a loop for 15 receiving a supporting-hook, substantially as set forth.

2. The combination with an incandescent-electric-lamp socket of an insulated handle, consisting of two separable parts adapted to engage the end of the socket, and having channels in their meeting faces to receive the conducting-wires and formed to provide a loop for receiving a supporting-hook, and means for holding the parts together and clamping the conductor-wires, substantially as set forth. 20 25

In witness whereof I have affixed my signature, in presence of two witnesses, this 10th day of September, 1903.

PATRICK J. CAHILL.
